United States Patent Office.

JAMES SHEEDY, OF NEW YORK, N. Y.

Letters Patent No. 95,152, dated September 21, 1869.

IMPROVED ATOMIZER FOR ADMINISTERING MEDICINES.

The Schedule referred to in these Letters Patent and making part of the same.

To all whom it may concern:

Be it known that I, JAMES SHEEDY, of the city, county, and State of New York, have invented a new and useful Improvement in Atomizers, of which the following is a full, clear, and exact description, reference being had to the accompanying drawing, forming part of this specification, and in which—

Figure 1 represents a side elevation of an atomizer or spray-apparatus, having my improvement applied to it, and

Figure 2, a sectional view on a larger scale, taken as indicated by the line $z-z$ in fig. 1, of the portion of the apparatus embracing my improvement.

Similar letters of reference indicate corresponding parts.

My improvement relates to atomizers or spray-apparatus, used for surgical and other operations or purposes, in which the draught or current to produce the spray, or divide into atoms the medicated or other fluid, and to expel or direct it against the part to be treated, is established or produced by the agency of steam or vapor, formed in a generator carried by said apparatus, and heated by a lamp connected with the latter.

In using such apparatus for various surgical operations, it frequently is necessary to stop quickly and temporarily, for a longer or shorter period, the action of the spray on the part being treated. This, heretofore, could only be done in one of two ways, namely, either by removing the entire apparatus, which is objectionable, as when once set, its position, relatively to the wound or part under treatment, should be preserved, or by withdrawing the lamp from under the generator, which does not immediately arrest the flow of steam or vapor, and is, on many accounts, objectionable, but preferable, as regards safety, to a mere stop-cock, operating only to open and close the outlet from the generator to or through the pipe which establishes the current, as in merely shutting off escape from the generator, there would be great danger of the latter bursting, by reason of its remaining closed for a prolonged period, with the lamp burning under it, which might occur either purposely or accidentally, and during which time additional pressure is being formed in the generator, with no provision for its relief or escape.

To obviate these difficulties is the object of my invention, which consists in a combination, with the draught or jet-pipe of the apparatus, or outlet thereto from the generator, of a two-way cock, of certain construction, and side outlet or escape-pipe, the whole being so arranged as that, without disturbing the apparatus, or removing the lamp, the spray may be instantly stopped, and kept stopped for a longer or

shorter time, without risking explosion of the generator, by turning the cock so as to divert the flow from it through the side pipe, and away from the patient and operator; also, whereby, on turning the cock to establish communication between the boiler and blast or jet-pipe, the spray-action may be as rapidly restored; and, furthermore, such cock being so arranged as that, by still further turning it, all outlet from the generator may be temporarily stopped to provide for accumulation of pressure, if necessary, within the generator.

Referring to the accompanying drawing, the apparatus there represented is, in its general aspect and construction, similar to others in ordinary use, A being the frame, B, the boiler, heated by a lamp, C, and serving to supply steam, through an outlet or branch, D, to the jet-pipe or tube E, which establishes the current or draught that causes the ether or other fluid in the bottle F to be drawn up through the tube G, and to be split or divided into spray, and blown along the conducting-tube H, to the part or surface to be treated, said conducting-tube being suitably held to admit of its adjustment to such part or surface, and having a bottle or reservoir, I, under its inner end, to catch the drippings caused by condensation of vapor within it.

The general adjustment of the apparatus may be made by or through the handle J, and when once set, my improvement provides for no disturbance of it, nor yet of the lamp, during the treatment, even though it be necessary to make pauses in the distribution of the spray, as in certain cases is absolutely requisite.

Thus I provide the steam outlet D with a cock, K, having a main passage, a, and branch passage, b, in it, and working in a seat, L, that has a side passage or escape-pipe, M, branching from it in a direction which would not cause a current of steam, issuing from it, to be projected either against the patient or operator.

When this cock stands in the position shown in the drawing, through communication is established between the boiler B and jet-tube E, which keeps the apparatus at work distributing the spray, but when said cock is turned to put its main passage, a, out of such through communication, and, through aid of the branch-passage b, made to establish open connection between the boiler and the escape-pipe or passage M, then the steam, instead of flowing through the jet-pipe E, will have vent through the passage M, and no accident can possibly occur to the boiler.

Should the steam have run down too low in the boiler, from thus being allowed to escape, or from other causes be too weak, said cock, as will be appa-

rent from its construction, may be temporarily turned to shut off all escape from the boiler, thereby allowing fresh or additional steam to be generated.

The direction in which the cock stands turned may be indicated by giving a peculiar or nose-like form to its handle *d*, and observing the relation of the same to the boiler and jet or escape-pipes.

What is here claimed, and desired to be secured by Letters Patent, is—

In an atomizer or spray-apparatus of the character

described, the combination of the cock *K*, constructed substantially as specified, with the outlet *D*, from the generator to the jet-pipe, and with the lateral escape passage or pipe *M*, from the seat *L* of said cock, essentially as and for the purposes herein set forth.

JAMES SHEEDY.
